[57] CLAIM

The ornamental design for a truck platform, as shown.

DESCRIPTION

FIG. 1 is a top plan view of a truck platform showing
my new design;

FIG. 2 is a side elevational view thereof, the opposite
side being substantially a mirror image of the side
shown herein;

FIG. 3 is a bottom plan view thereof;

FIG. 4 is an end elevational view thereof, the opposite
end being substantially a mirror image thereof.

FIG. 1

FIG. 2
